UNITED STATES PATENT OFFICE.

WILLIAM L. ZELLER, OF SPRINGBAY, ILLINOIS.

WRENCH.

1,287,564.

Specification of Letters Patent.

Patented Dec. 10, 1918.

Application filed May 4, 1917. Serial No. 166,320.

To all whom it may concern:

Be it known that I, WILLIAM L. ZELLER, a citizen of the United States, a resident of Springbay, in the county of Woodford and 5 State of Illinois, have invented new and useful Improvements in Wrenches, of which the following is a specification.

This invention has reference to improvements in tools and relates particularly to a 10 wrench of the quick acting type, including a fixed and a movable jaw.

One of the objects of the invention is to provide the movable jaw with a rack and meshing with the rack, a worm for adjusting the movable jaw with respect to the fixed jaw, and in the provision of means including a lever for releasing the worm from the rack of the fixed jaw to permit said movable jaw to be moved longitudinally quickly 20 to an adjusted position, and upon the release of the lever to cause the worm to again mesh with the teeth of said rack for making fine adjustments of said movable jaw.

A further object of the invention is to 25 provide the tool with a movable and fixed jaw, said movable jaw having a rack and slideable through a housing secured to the shank of the fixed jaw; a worm adapted to have a meshing relation with the said rack 30 journaled in a bearing carried in and slideable relatively to said housing; a lever operatively connected with said bearing for reciprocating the same in the housing to release the worm from said rack, to permit 35 said movable jaw to be quickly moved to an adjusted position, and a spring acting in connection with said lever for returning the worm to meshing relation with the rack when the lever is released, whereby a fine adjustment may be made of said movable jaw.

That the invention may be more fully understood, reference is had to the accompanying drawing forming a part of the application, in which:

45 Figure 1 is a side elevation of my improved tool, the movable jaw, the lever and worm shown in adjusted position in dotted lines;

Fig. 2 is a longitudinal section view of 50 the tool with a part of the shank of the fixed jaw broken away;

Fig. 3 is a detail in plan of the housing and bearing for supporting the movable jaw and worm;

55 Fig. 4 is a sectional view as the same

would appear if taken on the line 4—4, Fig. 1, and

Fig. 5 is a sectional view as the same would appear if taken on the line 5—5 of Fig. 1, the shank of the movable jaw being 60 omitted.

Like characters of reference denote corresponding parts throughout the figures.

In the drawing, 1 designates the fixed jaw on the end of a shank 2 having a hand-hold 65 or gripping portion 3 for use by the operator when gripping the tool.

Suitably secured to the shank 2 adjacent to the jaw 1 is a housing 4, comprising side walls 5 connected by the transverse 70 webs 6 and 7, said webs 6 and 7 being spaced apart to form a guide-way, together with the walls 5 for the shank 8 having the movable jaw 9, said movable jaw 9 connected to or forming a part of said shank 8 and disposed at right angles thereto so as to co-act with the jaw 1. The walls 5 of the housing are formed with the oppositely cut-out portions 10, see Figs. 1 and 3, to provide a 75 guide-way. On the outside of one wall 5 if the housing 4 are provided the spaced ribs 11, the matching faces of which are beveled as at 12 and form a dove-tailed groove in which is adapted to slide the shank 13 of a rectangular open boxing 14, said boxing having the end walls 15 formed with the shoulder portions 16, so that a bearing is formed for the end walls of the boxing 80 between the cut-out portions 10 of the side walls 5 and between the matching walls 5 of said housing, as best seen in Fig. 3. In 85 said boxing 14 and between the end walls 15 is journaled a worm 17, said worm being normally in meshing relation with the teeth of a rack 18 cut or suitably formed on the shank 8 of the movable jaw 9. It is obvious 90 that by turning the worm in opposite directions, the shank 8 may be moved alternately end-wise in opposite directions to adjust the jaw 9 with respect to the jaw 1, the shank 8 95 having a sliding movement in the housing 4.

For a quick release of the worm 17 from the teeth of the rack 18, I provide the lever 19 preferably fulcrumed at 20 to the opposite walls 5 of the housing 4, and said lever has 105 the finger pressing portion 21, whereby the lever may be actuated and the forward end of said lever engages in the preferably V-shaped notch 22 in the lower portion of the shank 13 of the boxing 14. The lever is held 110

in a position retaining the worm 17 in meshing relation with the teeth of the rack 18, by means of the spring 23, the acting end of which bears against the wall of the finger 5 pressing portion 21 of said lever, said spring being preferably secured between the walls 5 of the housing 4 by the same screw which forms the fulcrum of the lever, the forward end of the spring bearing against the under- 10 side of one of said transverse webs 6 of the boxing. It is obvious that by pressing down upon the finger portion 21 of said lever and moving it into the dotted line position shown in Fig. 1, that the shank 13 will be recipro- 15 cated, moving the boxing 14 to release the worm 17 from the teeth of the rack 18 and thereby permit the shank 8 and jaw 9 to be quickly adjusted with respect to the jaw 1, and when adjusted to a desired position, 20 upon releasing the lever, the spring 23 will act to return the boxing to a position causing the worm 17 to engage with the teeth of the rack 18, whereby a finer adjustment of the shank 8 and jaw 9 may be made, if de- 25 sired. The engagement of the jaws 1 and 9 will limit the movement of the shank 8 in one direction, and a pin 24 connected with the rear end of the shank 8 adapted to en- 30 gage in the notch 25 in one wall 5 of the housing 4 will limit the movement of the shank 8 in the opposite direction.

The drawing illustrates the preferred construction of my tool, but it is obvious that modifications may be made without limiting 35 the scope or spirit of the invention, and I reserve the right to make such modification.

What I claim is:—

1. In a tool of the character described, in 40 combination, a jaw having a shank, a housing connected with said shank and provided with a guide-way, a jaw movable relatively to said first jaw and having a shank portion slidably carried in the guide-way of said housing and provided with a rack, a bearing 45 having a slidable relation with respect to said housing, a worm journaled in said bearing and normally meshing with the rack of said movable jaw, and means for moving said bearing for releasing the worm from the 50 rack.

2. In a tool of the character described, in 55 combination, a jaw having a shank, a housing connected with said shank and provided with a guide-way, a jaw movable relatively to said first jaw and having a shank portion slidably carried in the guide-way of said housing and provided with a rack, a bearing 60 having a slidable relation with respect to said housing, a worm journaled in said bearing and normally meshing with the rack of said movable jaw, a lever for moving said bearing to release the worm from the rack, and a spring acting to return the lever and bearing to their initial positions.

65 3. In a tool of the character described, in

combination, a jaw having a shank, a housing connected with said shank and provided with a guide-way, a jaw movable relatively to said first jaw and having a shank portion slidably carried in the guide-way of said 70 housing and provided with a rack, a bearing having a slidable relation with respect to said housing and formed with a shank extension, a guide-way for the shank extension of the bearing on said housing, a 75 worm journaled in said bearing and normally meshing with the rack of said movable jaw, and a lever engaging the shank of the bearing and when actuated, adapted to move the bearing to release the worm 80 from the rack.

4. In a tool of the character described, in combination, a jaw having a shank portion terminating in a hand grip, a housing connected with said shank and provided 85 with a guide-way extending parallel with the shank of said jaw, a jaw movable relatively to said first jaw and having a shank portion extending parallel with the shank of said first jaw and slidably in the guide-way of the housing, said slidably shank having a rack, a bearing slidably carried in said housing and movable at right angles to said slidably shank, a worm journaled in said bearing and normally meshing with said 90 rack, a lever having a fulcrum on said housing, one end provided with a finger pressing portion, and the opposite end in connection with said bearing, whereby, when the lever is actuated, the bearing is moved 100 to release the worm from the rack, and a spring for returning and holding the lever to its normal position.

5. In a tool of the character described, in combination, a jaw having a shank and 105 terminating in a hand grip, a housing including opposite plate portions connected with the opposite sides of said shank adjacent said jaw, said plates connected by web portions forming a guide-way, a jaw movable relatively to said first jaw and having a shank portion slidably carried in the guide-way formed by said plates and webs of the housing, said slidably shank having a rack, a bearing slidably carried in said 110 housing, a worm journaled in said bearing and normally meshing with said rack, and a lever for moving said bearing to release the worm from said rack.

6. In a tool of the character described, in 115 combination, a jaw having a shank and terminating in a hand grip, a housing including opposite plate portions connected with the opposite sides of said shank adjacent said jaw, said plates connected by web portions forming a guide-way, one of said plates formed with a guide-way on its outside face, a jaw movable relatively to said first jaw and having a shank portion slidably carried in the guide-way formed by said 120

125 130

plates and webs of the housing, said slidable shank having a rack, a bearing slidably carried in said housing and having a shank 5 slidable in said guide-way on the outside of one of said plates, said shank provided with a notch, a worm journaled in said bearing and normally meshing with said rack, a lever fulcrumed on said housing, one end 10 of said lever having a finger pressing portion, its opposite end engaging in the notch of the shank of the bearing, and a spring for holding the lever in normal position with the worm engaging the rack.

7. In a tool of the character described, in 15 combination, a jaw having a shank, a housing including opposite plates secured to said

shank adjacent said jaw, and connected by webs forming a guide-way, the outer portions of said plate formed with cut-out portions, a jaw movable relatively to said first 20 shank and having a shank portion slidably carried in the guide-way of said housing, and provided with a rack, a bearing slidably carried in said housing and having end walls guided between said plates, and in the cut- 25 out portions thereof, a worm journaled in said bearing between the end walls thereof and normally meshing with said rack, and a lever connected with said bearing and adapted to move the same to release the 30 worm from the rack.

WILLIAM L. ZELLER.
